UNITED STATES PATENT OFFICE.

CARL W. SWANSON, OF CHICAGO, ILLINOIS, ASSIGNOR TO APEX APPLIANCE COMPANY, OF CHICAGO, ILLINOIS, A CORPORATION OF ILLINOIS.

DESIGN FOR A WASHING-MACHINE TUB.

57,172.

Specification for Design.

Patented Feb. 22, 1921.

Application filed March 29, 1920. Serial No. 369,753. Term of patent 14 years.

To all whom it may concern:

Be it known that I, CARL W. SWANSON, a citizen of the United States, and a resident of Chicago, in the county of Cook and State of Illinois, have invented a new, original, and ornamental Design for Washing Machine Tubs, of which the following is a specification, reference being had to the accompanying drawing, forming a part hereof.

The figure is a perspective of a washing machine tub in accordance with my new design.

What I claim is:—

The ornamental design for a washing machine tub, as shown.

CARL W. SWANSON.
